(57) **CLAIM**

The ornamental design for combined safety glasses and pencil holder and pencil sharpener therefor, substantially as shown and described.

DESCRIPTION

FIG. 1 is a right perspective view of the present design.
FIG. 2 is a left perspective view of the present design.
FIG. 3 is a front elevational view of the present design.
FIG. 4 is a rear elevational view of the present design.
FIG. 5 is a right elevational view of the present design.
FIG. 6 is a left elevational view of the present design.
FIG. 7 is a top plan view of the present design; and,
FIG. 8 is a bottom plan view of the present design.
